* cited by examiner

Primary Examiner—Holly H. Baynham*Assistant Examiner*—Cynthia M. Chin(74) *Attorney, Agent, or Firm*—Keisling Pieper & Scott PLC; David B. Pieper; Trent C. Keisling(57) **CLAIM**

The ornamental design for a slanted top mount feedneck, as shown and described.

DESCRIPTION

FIG. 1 is a top view of a slanted top mount feedneck showing my new design;

FIG. 2 is a back view thereof;

FIG. 3 is a left side view thereof;

FIG. 4 is a front view thereof;

FIG. 5 is a right side view thereof;

FIG. 6 is a bottom view thereof;

FIG. 7 is an isometric view thereof; and,

FIG. 8 is a reduced environmental view thereof showing the feedneck connected to a paintball marker in a left side orientation with a grip connected to the upper part of the feedneck where the broken lines in the drawings are used for illustrative purposes only such that the grip and the marker body form no part of the claimed design.
